UNITED STATES PATENT OFFICE.

GUS MOHAMMED, OF DETROIT, MICHIGAN.

COMBINATION CHAIR AND IRONING-BOARD.

1,359,723.

Specification of Letters Patent. Patented Nov. 23, 1920.

Application filed June 28, 1920. Serial No. 392,857.

To all whom it may concern:

Be it known that I, GUS MOHAMMED, a subject of the Turkish Ruler, residing at Detroit, county of Wayne, State of Michigan, have invented certain new and useful Improvements in Combination Chairs and Ironing-Boards; and I do hereby declare the following to be a full, clear, and exact description of the invention, such as will 10 enable others skilled in the art to which it appertains to make and use the same.

This invention relates to a combined chair and ironing board and consists substantially of a strong chair, provided with a displaceable back, so arranged that by a simple manipulation of the back the same will take the form of an ironing board, the chair being also provided with a hinged seat which acts as a support for the forward end of 15 the ironing board when said seat is raised to a vertical position.

The principal object of the invention is to provide a device of this character, simple in construction and operation, which may 20 be used as a chair alone but which can be quickly and conveniently readjusted to form an ironing board and, by reason of its novel construction, can be so adjusted that the ironing board will be supported in such a 25 manner that a substantial and well balanced article of furniture will be produced.

Briefly stated the invention comprises a chair of a substantial type provided with the usual stiles or back supporting posts, between which is slidably positioned a solid back in the form of an ironing board, made in two sections hinged together, the upper ends of the stiles being provided with pivot pins adapted for sliding engagement with 30 guide ways provided on the opposite side edges of the solid back section, so that said back section will be mounted for both vertical and swinging movement on the pivot pins. The hinge section of the back is 35 adapted to be extended or elevated by bracket rods, the inner ends of said rods having sliding engagement with guideways formed on the inner faces of the chair stiles or back supporting posts. The seat 40 of the chair is hinged at its front edge and adapted to be swung to a vertical position for supporting the forward end of the ironing board when the back is so adjusted, the rear end of the board being supported by the 45 chair stiles upon the pivot pins.

In the accompanying drawings, in which

like numerals designate like parts throughout the several figures:

Figure 1 illustrates the manner of supporting the ironing board upon the chair; 60 Fig. 2 is a front elevation thereof;

Fig. 3 is a plan view;

Fig. 4 shows the device in its collapsible position, assuming the form of an ordinary chair; 65

Fig. 5 is a rear elevation;

Fig. 6 is a detail view showing the hinged connection between the two sections of the ironing board and a part of the guideway in the main section and means of securing 70 the bracket rod to the hinged section; and

Fig. 7 is a detail, partly in section illustrating the sliding connection between the guideway of the ironing board and the pivot pin in the upper end of the chair stile. 75

Referring to the drawings in detail, particularly Fig. 1, the chair 1 is provided with the usual front and rear supporting legs 2 and 3 and back supporting posts or stiles 4. Positioned between the stiles 4 is a solid 80 back, of ironing board shape, comprising a main section 5 and a hinged section 6. At the upper ends of each of the stiles 4 are provided pivot pins 7 which are adapted to slide within, and engage guideways 8 85 arranged on the opposite side edges of the main section 5. Supporting the hinged section 6 and secured thereto by straps 7¹ are bracket rods 8¹, the inner ends of said rods being mounted for sliding engagement in 90 guideways 9 arranged on the inner faces of the stiles 4.

For supporting the forward end of the ironing board the seat 10 of the chair is 95 pivotally secured to the forward edge thereof and adapted to be raised to a vertical position, as clearly shown in Fig. 1, the rear end of the main section of the ironing board being supported upon the pivot pin 7. The rear end of the board being supported upon 100 the upper ends of the stile 4 obviously elevates the ironing board to such an extent that the seat itself when elevated is not sufficient to support the ironing board in a horizontal position and therefore some extensible means 105 will have to be provided. To accomplish this the inner or upper edge of the seat is provided with a horizontal recess 11, terminating in two vertical recesses 12, which recesses are adapted to receive a spring support 13. This 110 support 13 is constructed with a horizontal intermediate portion and downwardly and

outwardly extending spring legs or end portions which fit within the horizontal recess 11 and vertical recesses 12 respectively, when the seat is in its closed position. When the 5 seat is elevated, as a support for the forward end of the ironing board, the spring support 13 is partly withdrawn from the recesses 11 and 12 and held in this position by the shoulders 14 snapping over the upper 10 outer edges of the recesses 12, owing to the spring like tendency of the downwardly extending legs of the support 13. A slight inward pressure on these legs will allow the said support 13 to telescope within the 15 recesses 11 and 12 when desired.

When the device is used as a chair alone as illustrated in Figs. 4 and 5, the main section 5 of the ironing board will be vertically positioned between the stiles 4 of the chair 20 and the hinged section 6 will be folded down and lie flat against the main section 5, as clearly shown in the drawing, the spring support 13 being telescoped within the seat 10 and the seat closed in its normal position.

25 In converting the chair into an ironing board the main section 5, carrying with it the hinge section 6, is elevated sufficiently to allow the lower end of the main section to clear the seat frame of the chair, the guideways 8 coöperating with the pivot pin 7 in an obvious manner. During this movement the bracket rods 8¹ which are in sliding engagement with the guideways 9 on the chair stiles 4, are also elevated, the guideways 9 30 being long enough to allow the main section 5 to clear the seat frame. When the section 5 is elevated sufficiently to allow the lower end thereof to clear the seat frame said section is drawn forward and downward and 35 40 then swung upwardly about the pivot pin 7 until said section assumes a horizontal position, as shown in Fig. 1, wherein the pivot pins 7 are at the extreme rear ends of the guideways 8. During this movement the hinge section 6 will be caused to straighten out in line with the main section 5. After both of the sections 5 and 6 are in their horizontal positions the seat 10 is elevated and the spring support 13 withdrawn from the 45 50 recesses 11 and 12, assuming the position as clearly shown in Fig. 2, the upper portion of said spring support fitting in small recesses in the under side of the ironing board, provided for the purpose.

55 In this position of the ironing board, with respect to the chair, it will be noted that the supports for the ironing board, comprising the chair back posts 4 and the elevated seat 10, are so positioned that the ironing board 60 is well balanced thereon and the weight thereof equally distributed. The box-like

seat frame may conveniently be used for holding sad irons when the same are not in use.

What I claim is:

1. In a chair, the combination with a displaceable back, adapted to form an ironing board, of a seat pivoted to swing to a vertical position, said back comprising a main section and a hinge section positioned between the stiles of the chair back, grooved guideways along the opposite side edges of the rear half of the main section, pivot pins carried by the upper end of each stile for sliding engagement with the guideways, permitting the elevation of both sections and the subsequent forward extension of said main section and means connecting the hinged section to the chair stiles, for simultaneously extending and supporting said hinged section upon the forward extension of the main section, to form an ironing board and a support for the forward end of said ironing board comprising the vertically elevated hinged seat. 65 70 75

2. In a chair, the combination with a displaceable back, adapted to form an ironing board, of a seat pivoted to swing to a vertical position, said back comprising a main section and a hinge section positioned between the stiles of the chair back, grooved guideways along the opposite side edges of the rear half of the main section, pivot pins carried by the upper end of each stile for sliding engagement with the guideways, permitting the elevation of both sections and the subsequent forward extension of said main section, bracket rods pivotally connected to the hinged section and having their opposite ends slidably positioned in guideways carried by the chair stiles, for simultaneously extending and supporting said hinged section upon the forward extension of the main section, to form an ironing board and a support for the forward end of said ironing board comprising the vertically elevated hinged seat. 80 85 90 95 100 105

3. In a chair, the combination with a displaceable back, adapted to form an ironing board, of a seat pivoted at the forward edge 110 of the chair to swing to a vertical position, a recess formed in the upper or inner edge of said seat, a bent spring supporting rod carried within said recess and adapted to be extended therefrom to form a support for the 115 forward end of the ironing board, when the back is so adjusted, and the rear of said board supported between the stiles of the chair back.

In testimony whereof I affix my signature. 120

GUS MOHAMMED.
